DEVICE FOR CLAMPING THE THREADS
OF A WARP

Alois Altenweger, Uster, Switzerland, assignor to Zellweger A.G., Apparate- und Maschinenfabriken, Uster, Uster, Switzerland, a corporation of Switzerland

Filed July 28, 1958, Ser. No. 751,552

Claims priority, application Switzerland Sept. 10, 1957

7 Claims. (Cl. 28—22)

The present invention has for its object the provision of a device for clamping warp threads which device includes a comb element so disposed that the several threads comprising the warp lie respectively in the spaces between the teeth comprising said comb and also includes a tensioning means which acts to press the warp threads against suitable elements which act as pressure pads and which are normally integral or form a unitary structure with the comb teeth. Such warp clamping and tensioning devices are commonly utilized in pairs when employed in connection with warp tying machines, thread drawing-in machines and the like, so that the individual threads comprising said warp may be presented to a thread separating means in an orderly and parallel fashion so that they may be separated from the warp as individual threads for a subsequent operation.

Other objects of this invention will appear from the following detailed description and the accompanying drawing.

In the drawing, in which there is shown a preferred embodiment of an apparatus designed and constructed in accordance with the present invention:

Fig. 1 is a sectional view of the device of this invention taken across the longitudinal axis of the comb,

Fig. 2 is a lateral and front elevational view of said device taken along the length of the comb, said view also being partly in section, and

Fig. 3 is a plan view of a portion of the thread tensioning means of this invention, which view is taken in a direction vertical to the plane of the warp.

Like numerals indicate like parts throughout the several views of the drawing.

The comb which forms one of the essential elements of the device of this invention comprises, as shown in Figures 1 and 2, a plurality of teeth 1 individually having root portions which are separated from each other by means of spacing elements 2 and are also held in position by means of an oblong rectangular element or sleeve 3 which surrounds the feet or root portions of the teeth 1. On both ends of each comb there are provided suitable locking elements (not shown) which prevent the several teeth and the spacing elements 2 which separate the teeth from falling from the open ends of sleeve 3. The length of the comb is equal to at least the width of the warp being acted upon. The comb can be so placed in position in cooperation with a warp held under tension that the spaces between the teeth 1 may contain one or more warp threads 4 as shown in Fig. 2.

In the embodiment of the clamping device shown in the drawing, the several teeth 1 are each provided with a hole through which a circular rod 5 which is equal in length to the comb, can be passed after the warp threads have been placed in position between the comb teeth. In this manner it is possible, among other operations, to place the comb into the warp as long as it is on a finishing machine and, after closing or locking the spaces between the teeth to maintain the individual threads in the proper sequence or order even after cutting the warp. In lieu

2

of the thread blocking means shown, it is also possible to close the spaces between the comb teeth and prevent the warp threads from slipping out of position by placing a cover over the points of the comb teeth.

Such a comb is particularly useful if it can be employed as a part of warp clamping means during the tying of the warp with the aid of a warp tying machine.

For this purpose the comb teeth 1 are provided with surfaces 6 and 7 against which abut corresponding parts of a clamping device. This clamping device comprises,

for example, a generally rectangular profiled hollow bar or sleeve 8 which contains a bar 9 of L-shaped profile while is laterally movable and displaceable therein. The bars 8 and 9 have jaw portions 10 and 11 respectively, which can be brought closer together by movement toward each other when sawtooth faced or profiled rods 12 and 13, which lie within the hollow bar 8 and rest on the horizontal portion of the L-shaped bar 9, are moved oppositely and preferably simultaneously in the direction shown by each of the arrows in Fig. 3. This simultaneous and opposed motion of sawtooth-faced cams 12 and 13 can be effected in a manner well known to the art by the use of a suitable eccentric drive means or a geared screw drive means, for example. The lateral motion of the L-shaped profiled bar 9 across the width of the profiled bar 8 must be such that the comb teeth 1 can pass between the jaws 10 and 11 to enter the space below. If the sawtooth profile cams 12 and 13 are displaced relative to each other in the direction of the respective arrows shown in Fig. 3, the jaw 11 moves to the left and, as a consequence, the comb is forced downward into the clamping means. The jaws 10 and 11 thereby exert a pressure on the warp threads 4 which are thus held against the surfaces 14 and 15 of the sleeve 3 which is firmly and rigidly attached to the comb teeth 1.

The surfaces 14 and 15 are advantageously so designed that they lie substantially in but a single plane and so that the said plane will pass through the comb teeth at some point between their base and the points of the teeth. In this way the warp threads undergo little or no bending or other distortion when they are being held in the aforesaid clamped position.

In order to improve the performance of the clamp it is possible to cover either the surfaces 14 and 15 or the jaws 10 and 11 with a flexible or yielding material or to form them of such a material. This expedient is preferred since the use of such a flexible material as a surface allows a certain amount of distortion and permits warp threads of quite different counts to be held in clamped position in the same place.

What is claimed is:

1. A device for clamping the threads of a warp comprising a comb including an oblong element and spaced teeth extending therefrom and forming gaps receiving the warp threads, and movable clamping means operatively associated with said comb for pressing the warp threads received in the gaps between the teeth of the comb against said oblong element.

2. A device as defined in claim 1 in which said teeth and said movable clamping means have corresponding surface portions slidably engaging one another and guiding said movable clamping means into the thread clamping position.

3. A device according to claim 1 in which said teeth individually have a free end and a root portion received in said oblong element and a portion whose extension, seen in the longitudinal axis of the comb, increases in the direction away from said root portion for forming inclined surfaces on said teeth laterally of the comb, said clamping means being movable towards and from the sides of said comb and having inclined surfaces cor-

responding to and slidably engaging said inclined surfaces of said teeth for moving said comb in the direction towards the free ends of the teeth and pressing said element against said clamping means.

4. A device according to claim 1 in which said oblong element has a substantially plane surface portion on which lie the warp threads received between said teeth, said surface portion being located substantially in the plane formed by the warp threads, and said clamping means pressing the warp threads against said surface portion.

5. A device according to claim 1, including closing means removably extending through said teeth for closing the gaps between the teeth and retaining the warp thread in the gaps.

6. In a warp clamping device for clamping the several threads of a warp in substantially parallel arrangement, the combination of an upper hollow sleeve and a lower hollow sleeve, said upper hollow sleeve containing the root portions of a plurality of spaced teeth extending downwardly into said lower sleeve thereby forming a comb substantially coextensive in length with said upper and lower sleeves and adapted to receive warp threads

therebetween, means cooperating with said teeth and said lower sleeve for holding said upper and lower sleeves in fixed position relative to each other and including adjustable clamping means positioned in said lower sleeve adapted to press upward against the warp threads between the comb teeth and cause said threads to engage the lower surface of the upper sleeve.

7. A warp clamping device in accordance with claim 6 wherein the warp thread clamping means in said lower sleeve comprises a jaw adapted to press upward against the warp threads on positive lateral displacement and cause said threads to engage the lower surface of the upper sleeve, and a pair of saw-toothed, horizontal cams in operative contact with said jaw for actuating said jaw into upwardly pressing engagement by the displacement relative to each other of said cams.
